United States Patent Office

Des. 202,641
Patented Oct. 26, 1965

202,641

CLOCK

Frederick A. Burke, Mamaroneck, N.Y., assignor to Sunbeam Corporation, Chicago, Ill., a corporation of Illinois

Filed Jan. 8, 1965, Ser. No. 83,356

Term of patent 14 years

(Cl. D42—7)

Fig. 1

Fig. 2

Fig. 3

Fig. 4

FIG. 1 is a front elevational view of a clock showing my new design;

FIG. 2 is a top plan view thereof;

FIG. 3 is a side elevational view thereof; and

FIG. 4 is a cross-sectional view thereof taken on line 4-4 of FIG. 1.

I claim:

The ornamental design for a clock, as shown.
